UNITED STATES PATENT OFFICE.

ENOS HOOK, OF NEW YORK, N. Y.

STEAM-BOILER.

SPECIFICATION forming part of Letters Patent No. 599,609, dated February 22, 1898.

Application filed May 14, 1897. Serial No. 636,473. (No model.)

To all whom it may concern:

Be it known that I, ENOS HOOK, of New York city, in the county and State of New York, have invented new and useful Improvements in Steam-Boilers, of which the following is a full, clear, and exact description.

This invention relates to improvements in steam-boilers of a type having depending water-tubes hung from the crown-sheet of the water-chamber, so as to receive heat from the fire-chamber and the hot-air passage at the rear of said fire-chamber.

The object of the invention is to provide features of improvement for a steam-boiler of the designated type whereby increased efficiency is attained by the provision of greater heat-receiving area within the boiler than in boilers of the class above specified as heretofore constructed.

The invention consists in the novel construction and combination of parts, as is hereinafter described, and defined in the appended claims.

Reference is to be had to the accompanying drawings, forming a part of this specification, in which similar characters of reference indicate corresponding parts in all the figures.

Figure 1 is a sectional side view of the boiler, showing part of the improvement thereon. Fig. 2 is a sectional plan view essentially on the line 2 2 in Fig. 3. Fig. 3 is a transverse sectional view substantially on the line 3 3 in Fig. 2. Fig. 4 is an enlarged vertical sectional view of novel details substantially on the line 4 4 in Figs. 2 and 5, and Fig. 5 is an enlarged sectional detail view on the line 5 5 in Fig. 4.

The exterior shell of the boiler in this exemplification of the applied improvements is preferably made cylindrical, as shown at 10 in the drawings, and said shell is set in place on masonry A, but it is to be understood that the boiler-shell may, if desired, be otherwise supported and protected at the sides.

An interior shell 11 is held in position within the outer shell 10 by its secured engagement with the boiler-head plates 12 and 13, that are respectively affixed at the front and rear ends of the said shells. The front head-plate 12 is apertured to afford access to the interior of the fire-chamber B, which is produced at the front end of the boiler by the

transverse bridge-wall C and grate-bars D. The upper surface of the interior shell 11 is flattened to provide a crown-sheet 11^a, and numerous water-tubes 14 hang from the crown-sheet. The tubes 14 are open at their upper ends and closed at the lower ends, which adapts each tube to receive water from the space between the shells 10 and 11. 55 60

Over the grate-bars and in the fire-chamber B the depending water-tubes 14 are shortened, so as to permit space for fuel on the grate-bars, the major portion of the spaced water-tubes occupying the hot-air chamber and 65 draft-passage B', that extends from the fire-chamber B behind the bridge-wall C.

The usual transversely-disposed crown-bars 15 are affixed at suitable intervals on the crown-sheet by bolts which project from said 70 sheet, whereby the crown-sheet is substantially braced against disrupting pressure of steam generated in the boiler.

On the outer shell 10 a dry-steam dome or chamber 16 is preferably placed and is connected with said shell by the neck-pipes 17, as shown in Fig. 1. The draft-passage B' 75 communicates at its rear end with a transverse passage B², connected at its bottom with a rearwardly-extending horizontal flue 80 B³, and this flue at its rear end communicates with a vertical draft-chimney, (not shown,) so that the hot products of combustion evolved by burning fuel on the grate-bars D pass back between the depending 85 water-tubes 14, and thence to a stack at the rear end of the boiler. The foregoing description of parts briefly indicates the usual construction of boilers having depending water-tubes and is not broadly claimed as being 90 a feature of the present invention.

In boilers of the depending water-tube type as heretofore constructed a vacant space is produced at each side of the crown-sheet if the inner shell 11 is cylindrical. One 95 feature of the present improvement is designed to utilize these spaces and provide longitudinally-extended water-tubes therein, which will greatly increase the water-heating area in the boiler. To this end four 100 header-boxes 18 are provided, two being located at each side of the depending water-tubes 14 near the front and rear ends of the shell 11. The end walls of each header-box

are parallel and have one side wall convexly curved to adapt said side for intimate contact throughout its area with the inner side of the shell 11, and the boxes 18 are firmly secured upon said shell by any suitable means.

- The front and rear walls of the header-boxes 18 are provided with circular apertures suitably spaced apart, and in the spaced ori-fices in each pair of boxes a set of water-tubes 19 are secured by their ends in a water-tight manner. The apertures in the parallel walls of the header-boxes that are spaced from those wherein the water-tubes are fixed have bonnets 20 secured over them by any suitable means, preferably as shown in Fig. 4, where cross-bars and bolts are represented as means for clamping the bonnets over the hand-holes in the outer walls of the header-boxes.
- 20 The convex sides of the header-boxes 18 and adjacent portions of the shell 11, engaged therewith, are suitably apertured, as at *a* in Figs. 4 and 5, which permits water from the water-space in the boiler to enter the header-boxes and circulate through the water-tubes 19. The covered hand-holes that are opposite the water-tubes at each end enable them to be cleaned by the insertion of a scraper or brush.
- 25 30 The annular water-space formed between the inner shell 11 and outer shell 10 of the improved steam-boiler may be measurably widened toward the upper surface of the inner shell 11 by disposing the shell 10 as shown in Fig. 3.

In the annular water-space extending from one side edge of the crown-sheet to the opposite side edge thereof a number of rows of spaced heat-conveying flues 21 are held by their ends in the front and rear head-plates of the boiler, these spaced flues being ar-40 ranged to occupy such relative positions in the water-space as will permit a free circula-tion of water around them, as shown in Figs. 2 and 3, room being afforded for the location of a hand-hole *b* and bonnet covering the same at each end of the boiler, as shown in Figs. 1 and 3.

The construction and arrangement of the 50 longitudinally-extending water-tubes 19 and longitudinal flues 21 economically utilize the vacant spaces in a boiler of the depending-water-tube class. The operation, briefly de-scribed, is as follows: The products of com-55 bustion evolved in the fire-chamber B pass rearwardly between the water-tubes 14 in the passage B' and at the rear enter the trans-verse passage B². Thence the heat and gases pass forwardly through the longitudinal flues 60 21, thence back beneath the shell 10 to a pas-sage leading out to a chimney. (Not shown.)

It will be evident that the products of fuel consumed will be brought intimately into contact with the exterior of the water-tubes 65 19, as well as the interior of the flues 21, and impart a larger proportion of heat to the wa-

ter in the boiler for the generation of steam than is effected in boilers not having the im-provements.

Having thus described my invention, I 70 claim as new and desire to secure by Letters Patent—

1. In a steam-boiler, the combination with an outer and an inner shell, end walls for the boiler, and water-tubes depending from the 75 top wall of the inner shell to receive heat from a fire-chamber in the inner shell, of wa-ter-tubes secured by their ends within header-boxes, affixed to the inner shell of the boiler and in open communication with the wa-80 ter-space of said boiler, substantially as described.

2. In a steam-boiler, the combination with an outer and an inner shell, walls engaging the ends of said shells to produce an annular water-space for the boiler, and water-tubes 85 depending from a flat crown-sheet on the in-ner shell so as to be enveloped by heat pro-duced in a fire-chamber within the inner shell, of sets of longitudinally-disposed water-tubes at opposite sides of the inner shell, between 90 the depending water-tubes and said inner shell, and a header-box for each end of each set of tubes, which boxes are secured on the inner shell and are in open communication with the annular water-space of the boiler, 95 substantially as described.

3. In a steam-boiler, the combination with an outer and an inner shell, end walls for the boiler, spacing the inner shell from the outer shell, a crown-sheet on the inner shell, crown-bars therefor, and water-tubes depending from said crown-sheet between the crown-bars, of hollow header-boxes secured on the inner wall of the inner shell, between said shell and the depending water-tubes at each 100 side of the boiler, and horizontal water-tubes having their ends affixed in one of the walls of the header-boxes and spaced apart therein, the opposite walls of said header-boxes being 105 apertured and said apertures being closed, 110 the sides of the boxes attached to the boiler-shell being in open communication with the water-space of the boiler, substantially as de-scribed.

4. In a steam-boiler, the combination with 115 an outer and an inner shell, end walls for the boiler, spacing the inner shell from the outer shell, and depending water-tubes closed at their lower ends and hung from the upper side of the inner shell, of series of horizon-tally-disposed water-tubes at each side of the 120 depending tubes, said water-tubes having their ends in open communication with header-boxes communicating with the water-space of the boiler, and series of heat-conducting 125 flues located in the water-space of the boiler and affixed at their ends in the end walls of the boiler, substantially as described.
